UNITED STATES PATENT OFFICE.

ALEXANDER BROOKS STEVENS, OF OAKLAND, CALIFORNIA, ASSIGNOR TO SCHMIDT LITHOGRAPH COMPANY, OF SAN FRANCISCO, CALIFORNIA, A CORPORATION OF CALIFORNIA.

PACKAGE-DISPLAY EASEL.

Application filed May 27, 1924. Serial No. 716,218.

To all whom it may concern:

Be it known that I, ALEXANDER BROOKS STEVENS, a citizen of the United States, residing at Oakland, in the county of Alameda,

- 5 State of California, have invented a new and useful Package-Display Easel, of which the following is a specification in such full and clear terms as will enable those skilled in the art to construct and use the same.
- 10 This invention relates to an easel intended for the purpose of displaying packages of various sizes slightly raised from the counter on which the easel is placed while at the same time, it provides two wings or display cards at the back of the package support.

An object of the invention is to produce one easel which is capable of being shipped flat in the shipping package of the cartons 20 or bottles to be displayed, thereby conserving space.

Another object of the invention is to produce a cut out shape which will produce a very strong form of easel which will have 25 locking tabs and cuts to insure holding the easel in the proper position to make a good display.

Another advantage of this easel is that the supporting stage may be partly cut out as 30 indicated in the figures in dotted lines where it may be desirable to more securely hold round or ball-shaped objects.

Another object of the invention is to display the object ahead of the reading matter 35 panels, the object appearing in the space between the two panels.

Another object of the invention is to produce an easel with a series of folds which will give a solid and substantial stand without gluing or stapling, all made in a single 40 piece.

In the drawing on which the same reference letters and numbers indicate the same part throughout.

45 Fig. 1 is a front elevation of the easel set up for use.

Fig. 2 is an edge elevation of the easel set up.

Fig. 3 is a plan view of the easel and Fig. 50 4 is a plan view of the cut and creased blank which forms the easel.

The blank forming the easel is cut and scored to produce the various panels and tabs to lock the panels in the set up condition numbered from 1 to 10 inclusive. 55

The panels 3, 4, 5, 8 are all substantially rectangular except that the panel 5 forming the floor on which the package rests has two tabs 6 and 7 at its upper corners to aid in supporting the display panels 1 and to hold 60 them in position.

The display panels 1 and 9 are so arranged that a number of advertisements may be added thereto with little changes or no change in the form of the collapsed easel. 65

It will be seen that card is creased along the line 11 to 15 while it is cut out. At two separate places to allow the necessary space to set in the locking "tabs." The tabs 6 and 7 are intended for a stiffening for the 70 display cards 1 and 9 and they extend under the object support.

It will be seen that on folding the receptacle to the position shown in Figs. 1 to 3, that it is possible to have both the tabs 2 75 and 10 pass into slots 14 and 15 in the back of the base and at the same time the base rests on the upper edges of the panels 3 and 8, while the side wings 1 and 9 are held firmly 80 in place by the tabs 6 and 7.

The various shaped receptacles may be displayed on the sleeves but only comparatively small objects can be used with this easel as the size card necessary to be used causes an increase in the blank size very 85 rapidly, so the full size of the commercial blank is very quickly reached.

It is also to be noted that with the panel 5 passing into the slots 19 and 20 and with the tabs 2 and 10 passing into the slots 21, 22, that the shelf 5 rests on the top of the panels 3 and 8, see Fig. 3, which gives a very strong construction, not easily broken while it is very easily set up.

The display panels 1 and 9 may be of any 95 desired height and breadth as may be possible with the paper stock used.

What I claim is as follows, but modifications may be made in carrying out the invention described above within the purview of 100 the annexed claim.

A display easel comprising a paper stock

blank cut and scored to produce a plurality of panels and tabs, two of said panels lying in substantially the same plane at the back of the object shelf, when the easel is set up for use, the shelf having slots to receive tabs on the display panels and the display panels having slots to receive the edges of

the shelf, whereby the shelf and panels are firmly secured together, and the shelf is supported by vertical members at its front ¹⁰ and at its opposite ends.

In testimony whereof I have hereunto set my hand this 17th day of May 1924.

ALEXANDER BROOKS STEVENS.
